DANIEL BULL, OF AMBOY, ILLINOIS, ASSIGNOR TO J. B. BOOKER AND
W. S. BEST.

Letters Patent No. 62,245, dated February 19, 1867.

IMPROVED TABLE-LEAF SUPPORTER.

The Schedule referred to in these Letters Patent and making part of the same.

TO ALL WHOM IT MAY CONCERN:

Be it known that I, DANIEL BULL, of Amboy, in the county of Lee, and in the State of Illinois, have invented certain new and useful improvements in "Table-Leaf Supporters," and do hereby declare that the following is a full, clear, and exact description thereof, reference being had to the accompanying drawings, and the letters of reference marked thereon, making a part of this specification, in which—

Figure 1 represents an end view of a table, with side view of supporter; and

Figure 2 an inverted plan view of the supporter.

In the annexed drawings, A represents an ordinary dining table. Under the leaf B is secured the supporter. This supporter is composed of a metallic shell-shaped plate, a, provided with small ears, v v, with holes for attaching it to the table. Lying within the plate a is a small bar, e, with a pad, y, at the end, and having a curved portion, b, which supports the table leaf. There is an opening made in the plate a, directly beneath where the pad y rests, while directly above the pad is an opening in the table leaf, into which is inserted a coil-spring, x. d represents a metal strip having a notch at its lower end, and which is secured to the table frame directly opposite to the curved supporter b, so that when the leaf is up the end of the supporter strikes the strip and catches into its notch, firmly supporting the table. When it is desired to lower the leaf, press upon the pad y, which compresses the spring x and carries the end of supporter from the notch; then lower the leaf, and the curved supporter, passing around the table frame, goes upwards under the table top, as shown in red lines, fig. 1. The hinge s s of the bar e may be either used or dispensed with.

Having thus fully described my invention, what I claim as new, and desire to secure by Letters Patent, is—

The bar b, in combination with the strip d, as constructed, and the plate a, when said plate is constructed so as to protect the end of the bar e, over which it rests, and is provided with an opening through which the pad y is operated, substantially as and for the purpose specified.

In testimony that I claim the foregoing I have hereunto set my hand and seal this sixth day of November, 1866.

DANIEL BULL. [L. s.]
